(57) **CLAIM**

An ornamental design for a microphone, as shown and described.

DESCRIPTION

FIG. 1 is a perspective view of a microphone showing my new design;

FIG. 2 is a front view of the microphone of FIG. 1 thereof, wherein **8** indicates a portion which is shown in an enlarged view in FIG. **8**;

FIG. 3 is a rear view of the microphone of FIG. 1 thereof; FIG. 4 is a left side view of the microphone of FIG. 1 thereof;

FIG. 5 is a right side view of the microphone of FIG. 1 thereof;

FIG. 6 is a top view of the microphone of FIG. 1 thereof; FIG. 7 is a bottom view of the microphone of FIG. 1 thereof; and,

FIG. 8 is a partial enlarged view of the microphone of FIG. 2 thereof.

The broken lines depict portions of the microphone that form no part of the claimed design.

The dashed broken lines surrounding portions of the microphone in FIG. 2 and illustrated in the enlarged view of FIG. **8** forms no part of the claimed design.

1 Claim, 4 Drawing Sheets
